[57] CLAIM

The ornamental design for a combined cane and cue
stick, as shown.

DESCRIPTION

FIG. 1 is a front elevational view of a combined cane
and cue stick, showing my new design;

FIG. 2 is a bottom plan view thereof;

FIG. 3 is a top plan view thereof;

FIG. 4 is a front elevational view thereof showing the
parts in an exploded relationship;

FIG. 5 is a front elevational view of a cue stick formed
from the parts of the cane shown in FIG. 4;

FIG. 6 is a bottom plan view thereof;

FIG. 7 is a top plan view thereof; and

FIG. 8 is a front elevational view thereof showing the
parts in an exploded relationship.
